FOOT PEDAL OPENER FOR GARAGE DOOR
Louis Henry Willenbring, R.R. 4, Enid, Okla.
Filed Apr. 24, 1963, Ser. No. 275,310
6 Claims. (Cl. 268—42)

This invention relates generally to lifting devices and more particularly to a foot operated device to start the opening movement of an upwardly movable element such as the door of a garage or the like.

At the present time many buildings such as home garages, automobile repair shops, and storage buildings have heavy doors that slide or swing in an upward direction to an open position. While such doors may or may not be counterbalanced, it usually requires considerable strength to start them on their upward opening movement, and frequently the person desiring to open the door, must stoop to reach a handle near the bottom of the door.

The main object of the invention is to provide a lever device mounted on the door and thrusting against the floor or ground to initiate the opening movement of the door, thus overcoming inertia and eliminating stooping, the device being preferably operated by the foot of the operator.

The invention further contemplates a mounting plate or member fastened to one face of the door near the floor, a generally horizontal foot actuated lever disposed in substantially parallel relation to the plane of the door and having one end pivoted to the plate for a limited vertical swinging movement, preferably some spring means for normally holding the lever in an elevated position, and at least one fulcrum member depending from an intermediate portion of the lever for rocking engagement with the floor, the fulcrum member being pivotally suspended.

Another object is to provide a device of the above indicated character in which a plurality of the fulcrum members are pivotally suspended in longitudinally spaced relation along the lever to increase the extent to which the door may be moved upwardly by the swinging movement of the lever.

Another object is to provide a lifting or starting device for a vertically movable element such as a door which may be operated from either the outer or the inner side of the door.

Another object is to provide a foot pedal door opening device which is of simple construction so that it may be manufactured at a low cost, which may be quickly and easily applied to garage doors having various kinds of mounting means, and which is reliable and effective in operation.

With the above and other objects and advantages in view, the invention resides in the novel combination and arrangements of parts and the novel features of construction hereinafter described and claimed, and illustrated in the accompanying drawings which show the present preferred embodiments of the invention.

In the drawings:

FIG. 1 is an elevational view of the outer face of a portion of an upwardly opening door having the device applied thereto, the door being shown in its closed position and parts being broken away;

2

FIG. 2 is a sectional view taken on the line 2—2 of FIG. 1;

FIG. 3 is a detail view showing another fastening means for the lever;

FIG. 4 is a detail cross section through the foot lever taken on the line 4—4 in FIG. 1, showing the pivotal suspension of one of the fulcrum members;

FIG. 5 is a perspective of the mounting plate;

FIG. 6 is a detail elevational view of a modified form 10 of fulcrum member; and

FIG. 7 is a perspective view of another embodiment of the invention in which the device may be operated from only one side of the door.

Referring more in detail to the drawings the numeral 15 designates the lower portion of a door or other vertically movable element to be lifted, 11 the frame in which the door is suitably mounted for sliding or swinging movement in an upward direction, and 13 the floor or ground line. Such doors as used in home garages are variously constructed and variously mounted for upward opening movement; and the invention is especially useful in starting the opening movements of such doors. My lifting device is positioned near the horizontal center of the door and close to its bottom. As shown in FIGS. 1—5 the foot operated lever is U-shaped, that is it has two parallel arms, one at the outer side of the door and the other at the inner side of the door so that the device may be operated by a person on either side, but in the form shown in FIG. 7, the single foot lever is to be disposed on one side of the door, preferably the outer side.

The device comprises a mounting plate 15, at least one foot lever 16 pivotally supported from said plate and one or more fulcrum pins 17 which are pivotally suspended from the intermediate portion of the lever and are adapted to engage the floor or ground. The plate 15 may be of generally rectangular shape with openings 18 for screws 19 to fasten the plate to one face of the door. Along one edge of the plate is an upright right angularly bent flange 20 with a vertical slot 21 through which the lever projects to limit its swinging movement. At the opposite edge of the plate is a similarly bent flange 22 with apertures 23 to receive hooks on the ends of one or more coil springs 24 which may be used to normally hold the lever 16 at the top of the slot 21. Only one spring is shown and the hook on its other end is engaged in one of the openings 25 in the lever.

At the free end of the lever is an enlargement or foot piece 26 and its other end is suitably fixed to a cylindrical pivot 27 rotatably carried by the plate 15. When the device is to be operated from either side of the door, a second foot lever 28 may have the cylindrical pivot 27 integral with its inner end, the pin being of a length to project through the door, as shown in FIG. 2. In such case the inner end of the lever 16 may be fitted over a square or flat faced projecting end of the pivot 27 or it may have a transversely extending cylindrical opening 29 to receive the end of the pivot 27 and be fastened thereto by a transverse pin 30 or similar means. The pivot 27 rotates in a cylindrical bearing tube 31 which is of greater length than the thickness of the door 10 and which projects from the plate 15 around an opening 32 therein. Surrounding the projecting end of the bearing tube or

sleeve 31 is a washer 33 fastened by screws 34 to the inner face of the door. It will be noted that the two lever arms 16 and 28 are parallel and project in the same direction close to the opposite sides of the door, and together with the pivot portion 27 form a single U-shaped lever. 5

One, two or more of the fulcrum members or pins 17 may be provided on one or both of the levers 16 and 28, but I preferably use two or three on the lever 16 as shown in FIG. 1. These fulcrum members may be metal rods with right angularly bent upper ends 35 pivoted in downwardly projecting apertured ears 36 on the lever and fastened by cotter pins 37. The lower ends of the fulcrum pins or rods are preferably provided with enlarged portions or heads 38 having rounded lower faces for a rocking engagement with the floor or ground. If desired the heads 38 may be faced with rubber or provided with rubber cups 38a, as shown in FIG. 6. These fulcrum members are longitudinally spaced along the intermediate portion of the lever, the one closest to the pivot 27 being of a length to just contact the floor when the door is closed and the lever 16 is in its normal elevated position, as seen in FIG. 1. While the fulcrum pins may be of equal length, FIG. 1 of the drawing shows the pin 17 farthest from the pivot 27 slightly shorter than the others. When either of the levers 16 or 28 is pressed downwardly, the lever 16 will fulcrum on that first member 17 which will have a slight rocking movement as the door begins to move upwardly, and as the downward pressure on the lever continues the succeeding members 17 will successively serve as the fulcrum for the lever, as the door continues to move upwardly. The device thus overcomes inertia and starts the opening movement of the door. After the door has been moved upwardly from above two to six inches by depressing one of the foot levers, it requires very little effort to continue the movement to a fully opened position. The use of a spring to normally hold the lever in its elevated position is desirable because otherwise, when the foot is removed from the lever, its free end and the fulcrum members 17 would drop below the bottom edge of the door. 30

In the embodiment shown in FIG. 7 only one lever is used and it may be disposed on either side of the door. In this form the foot lever 16a which corresponds to the lever 16, has its inner end rotatable on a cylindrical pivot stud 27a that is welded to the mounting plate 15a. The lever may have a cylindrical opening to receive the pivot and may be rotatively retained thereon by a washer 40 and cotter pin 41. In other respects the construction and operation of this form of the invention are the same as the first described form. 40

It will be noted that the device may be quickly and easily applied to a garage door. In the single lever form it is only necessary to properly position the plate 15a and screw it on the door, while in the two arm lever form it is only necessary to bore a hole in the door for the bearing sleeve 31, then screw the plate 15 and washer 33 to the door, and then assemble the two arm lever. 50

From the foregoing, taken in connection with the accompanying drawing, it will be seen that novel and advantageous provision has been made for carrying out the objects of the invention, and while preferences have been disclosed, attention is invited to the possibility of making variations within the scope of the invention as claimed. 60

I claim:

1. A foot operated device for starting the opening movement of a vertically movable garage door or the like, comprising in combination, 65

(a) a foot operated lever,

(b) means for pivotally mounting one end of said lever on a vertically movable door near the bottom of the latter with the lever extending in a generally horizontal direction and swingable vertically in a plane substantially parallel with that of the door, 70

(c) upper and lower stop means coacting with the lever to limit its swinging movement, 75

(d) spring means normally holding the lever in engagement with said upper stop means, and
(e) at least one fulcrum pin pivotally suspended from an intermediate portion of the lever and having its lower end rockably engageable with the floor, said pin serving as a fulcrum for said lever when its free end is depressed by the foot of the user.

2. The device of claim 1 in which there is a plurality of said depending fulcrum pins of approximately equal length arranged in longitudinally spaced relation along the intermediate portion of the lever, said pins having their upper ends pivotally connected to the lever and their lower ends successively engageable with the floor during the downward movement of the lever. 10

3. The device of claim 2 together with a second depressible lever disposed at the opposite face of the door and arranged in substantially opposed relation to said first mentioned lever, said pivotal mounting means mounting both of said levers in laterally opposed relation for swinging movement in unison. 15

4. A foot operated device for starting the opening movement of a vertically movable garage door or the like, comprising in combination,

(a) a mounting plate adapted to be fixed to one face of a vertically movable door near the bottom of the latter,

(b) a foot actuated lever,

(c) an upright slotted flange on said plate to serve as a guide for said lever and to limit its swinging movement,

(d) means pivotally mounting one end of said lever on said plate, said lever extending in a generally horizontal direction and being vertically swingable in the slot of said flange, 30

(e) a plurality of fulcrum pins pivotally suspended from the intermediate portion of said lever, said pins being of approximately equal length and arranged in longitudinally spaced relation along said lever for successive engagement with the floor as the free end of said lever is moved downwardly, and 35

(f) a coil spring connected at one end to said plate and at its other end to said lever for normally holding said lever at the upper end of said slot. 40

5. The device of claim 4 in which said means for pivotally mounting said lever comprises a cylindrical pivot to one end of which said lever is fixed, a cylindrical bearing sleeve fixed to one face of said plate and adapted to extend through the door, together with a second depressible foot lever fixed to the other projecting end of said pivot and disposed along the face of the door opposite to that of said first mentioned lever, the two levers being disposed in laterally opposed relation. 45

6. Foot operated apparatus for initiating vertical opening movement of a vertically movable member relative to a fixed surface, comprising

a vertical mounting plate adapted to be secured to one vertical face of the member near the bottom thereof; a rigid lever pivotally connected at one end with said plate for pivotal movement about a horizontal pivot axis normal to said plate, the pivot axis of said lever being spaced a given distance from the lower edge of said plate;

stop means carried by said plate for limiting the upper extent of pivotal movement of said lever beyond a generally horizontal first position;

spring means connected between said lever and said plate for continuously biasing said lever toward the said first position in engagement with the stop means; and a plurality of longitudinally-spaced fulcrum means carried by said lever intermediate the ends thereof, the first one of said fulcrum means adjacent said pivot axis defining a first fulcrum point at an elevation lower than that of the pivot axis when said lever

is in the said first position, the remaining fulcrum means defining, in the direction from said first fulcrum means toward the free end of said lever, successive fulcrum points of successively higher elevations than said first fulcrum point when said lever is in the said first position, said fulcrum means being so arranged on said lever that upon downward pivotal movement of said lever, the successive fulcrum points, in the direction from said first fulcrum means to the free end of said lever, successively engage the fixed surface to progressively lift said member from said fixed surface.
